UNITED STATES PATENT OFFICE.

HERMAN W. HITZEMANN, OF ROSELLE, ILLINOIS.

FRAME-ADJUSTING MECHANISM.

1,070,129.

Specification of Letters Patent.

Patented Aug. 12, 1913.

Application filed June 4, 1912. Serial No. 701,593.

To all whom it may concern:

Be it known that I, HERMAN W. HITZEMANN, a citizen of the United States, residing at Roselle, in the county of DuPage and 5 State of Illinois, have invented a certain new and useful Frame-Adjusting Mechanism, of which the following is a specification.

My invention relates to improvements in 10 potato diggers, in which laterally revolving radial arms, secured to a disk, operate in conjunction with a plowshare; and the object is to furnish a framework, and wheels and axles to carry the same, for the mounting and operation of the mechanism described in my divisional application No. 15 731220 filed November 13, 1912.

Figure 1 is a plan view of my invention, showing it as ready to have a team hitched 20 thereto and operate it; Fig. 2 is a side elevation of the same.

Like numerals refer to like parts throughout the several views.

Referring to the drawings: 10 is a double 25 bar connecting the front and rear axles of the digger; 11—11 are brackets securing the bar on the rear axle. The axle passes through these pivot-wise, and is rigidly secured at its ends to the rear wheels.

30 12 is a vertical shaft, secured at its lower end to the forward axle; 13 is a sleeve, bolted to the front end of the double bars; 14 is a bracket, bolted upon the upper, enlarged part of the shaft, 12, and bearing the segment of a gear or quadrant; 15 denotes the lower end of the lever 17, extending in front of the shaft; 16 is a rod, pivoted on the lever, 17, and on the lug, 15 1/2, secured on the front end of the double bars; 17 is a lever, 35 pivoted on the bracket 14, at a point indicated. This lever extends in front of the shaft, 12, and is pivoted to the rod, 16, as stated above.

40 18 is a rod which is pivoted to the lever 17. The rod 18 is also pivoted to the plug 20 1/2.

45 18 1/2 is a spiral spring of the usual common form, and it is secured about the plug

20 1/2. This plug is fitted to engage with the cogs of the quadrant which is a part of 50 the bracket 14.

21—21 are bars, bolted to the bars, 10, and to the plowshare, 22.

The front end of the lug, 15 1/2, is slotted vertically to receive the clevis, 23, to which 55 a double-tree may be attached.

The top of the shaft, 12, bears the casting, 24, rigidly secured thereon. To this a pole is attached. The clevis, double-tree and pole are each of well known, common construction, 60 designed for hitching on a team to draw the digger.

A seat, 41, for the driver, is bolted centrally to the cross bar which is bolted to the double bars 10 near their rear end, and is so 65 located that the driver has within his reach the handle of the lever, 17.

To operate my invention a team is hitched to the digger by means of the double-tree and pole above named, which are both well 70 known, common construction; the driver, mounted on his seat, employs the handle, 17, with its spiral spring, 18 1/2, to depress the plowshare to the right level to bring its point below the potatoes in the hills. 75

What I claim as new and desire to secure by Letters Patent of the United States is—

In a frame adjusting mechanism, the combination of the double bars, 10, connecting the front and rear axles, the shaft, 12, bearing radial arm, 14, the sleeve, 13, inclosing said shaft, the lever, 17, pivoted on the arm, 14, rod, 16, pivoted at its upper end in the lower end of the lever, 17, extended, and at its lower end in the lug, 15 1/2, secured on 85 the front end of the double bars, and the plowshare, 22, substantially as and for the purpose specified.

In witness whereof I hereby subscribe my name and affix my seal to the foregoing 90 specification, at Chicago, Illinois, this 17th day of May, A. D. 1912.

HERMAN W. HITZEMANN. [L. S.]
